M. CHRISTELER

WINDOW CLEANING DEVICE

Filed July 14, 1926

FIG. 1

FIG. 2

INVENTOR
M. Christeler
BY *F. Ledermann*
ATTORNEY

UNITED STATES PATENT OFFICE.

MARIE CHRISTELER, OF UTICA, NEW YORK.

WINDOW-CLEANING DEVICE.

Application filed July 14, 1926. Serial No. 122,343.

The main object of this invention is to provide a window cleaning device which is simple in construction and inexpensive in cost of manufacture. The invention introduces a mobile carriage, a reciprocating pad, and strings for moving said pad in a vertical plane.

Another object is to provide a window cleaning device having a hinged arm which 10 may be rotated out of position when it is desired to replace one form of pad by another.

The above and other objects will become apparent in the description below, in which characters of reference refer to like-named 15 parts in the drawing.

Referring briefly to the drawing, Figure 1 is a side elevational view of the cleaning device as applied to a window.

Figure 2 is a rear end elevational view of 20 the same.

Referring in detail to the drawing, the numeral 10 indicates the lower horizontal bar of a window sash. Said bar is part of three additional members which encase a 25 window pane 11. The bottom bar 10 of the window sash saddles or is cradled in a U-shaped bracket consisting of a plate 12 and sides 13 and 14, which latter extend upwardly. The side 14 has a cut-out portion intermediate its length in which the lower end of a rectangular guide post 15 is pivotally secured by a pin 16. The U-shaped bracket is supported upon wheels 17 and 18 which are pivoted between plates 19 and 20, said plates 30 being angular and having one of the extending portions rigidly attached to the bottom of the U-shaped bracket. The post 15 serves as a guide for a pad 21 which is mounted on a block 22. The block 22 is provided with a 35 sleeve 23 which fits over the post 15 and is slidably mounted on the latter. At the upper end of the post 15, a grooved pulley 24 is rotatably mounted on a spindle 25. The 40 upper end of the block 22 has an eye hook attached thereto to which one end of a cable 26 is secured. This cable is trained about half the periphery of the grooved pulley 24 and extends downwardly to the lower end of the device at which point it is trained about 45 a grooved pulley 27, which latter is rotatably fixed between ears 28. An additional cable 29 is attached to the lower end of the block 22 and suspends downwardly toward the 50 lower end of the device and at the lower end 55 it is trained for a quarter of a turn around a grooved pulley 30 and then around the

smaller pulley 31 which is rotatably mounted beneath the pulley 30. This latter cable 29 then passes about a grooved pulley 32 which is secured in place in a similar manner as 60 the pulley 27. A collar bracket 33 is mounted on the side of the portion 14 of the U-shaped bracket and into this member the lower end of a longitudinally curved flat spring 34 is slipped. 65

The device is manipulated by moving or reciprocating the pad 21 in a vertical plane while the latter is in contact with the outer surface 35 or inner surface of a window pane. By pulling the cable 26, the pad 21 70 and block 22 are lifted upwardly as this block and pad are suspended from the cable. The opposite cable 29 when pulled, draws the pad downwardly and completes a reciprocating motion of the pad. The guide 75 post 15 is normally in upright position when the spring 34 is in place, and in order to rotate this guide post, the spring 34 is removed from the collar 33, after which the guide post may be freely rotated downwardly to 80 permit the operator to replace one pad with another.

It is to be noted that certain changes in form and construction may be made without departing from the spirit and scope of 85 the invention.

I claim:—

1. A device of the class described comprising a carriage, a guide post, a pad slidably supported thereon, said guide post being pivoted to said carriage, a grooved pulley at the upper end of said post, a pair of grooved pulleys at the lower end of said post, cables trained on said pulleys attached to said pad for reciprocating the latter, a strap mounted on said carriage, and flexible means in said strap for normally retaining the guide post in upright position when positioned adjacent a window. 90

2. A device of the class described comprising a carriage, a guide post, a pad slidably supported thereon, said guide post being pivoted to said carriage, a grooved pulley at the upper end of said post, a pair of grooved pulleys at the lower end of said post, cables trained on said pulleys attached to said pad for reciprocating the latter, a strap mounted on said carriage, flexible means in said strap for normally retaining the guide post in upright position when adjacent a window comprising a longitudinally curved flat spring having its lower end inserted in 100

105

110

115

said sleeve and its upper end engaging the guide post to resiliently retain said guide post in vertical position.

3. A device of the class described comprising a channelled carriage adapted to receive the lower rail of a window sash, a guide post pivoted to said carriage, a rectangular pad slidably supported thereon, said guide post being pivoted to one side wall of said carriage, a grooved pulley rotatably mounted at the extreme upper end of said post, a sec-

ond pulley mounted at the lower end of said post, cables trained on said pulleys for reciprocating the pad, said cables being attached to said pad from above and below the latter, a strap rigidly mounted on one side wall of said carriage, and spring means mounted in said strap extending upwardly adjacent the post for urging said post in upward position toward the window glass. 15

In testimony whereof I affix my signature. 20

MARIE CHRISTELER.
